(57) **CLAIM**

The ornamental design for a tear-off cap for a vial, as shown.

DESCRIPTION

FIG. 1 is a perspective view of a tear-off cap for a vial according to our new design secured to a mouth of a vial, the phantom showing of a portion of the vial forming no part of the claimed design;

FIG. 2 is a front elevational view of the tear-off cap for a vial of FIG. 1, the rear elevational view being identical to the front elevational view;

FIG. 3 is a right side elevational view of the tear-off cap for a vial of FIG. 1, the left side elevational view being identical to the right side elevational view;

FIG. 4 is a top plan view of the tear-off cap for a vial of FIG. 1; and,

FIG. 5 is a bottom plan view of the tear-off cap for vial of FIG. 1.
